UNITED STATES PATENT OFFICE.

LEONIDAS W. RICHARDSON, OF DUSTIN, TENNESSEE, ASSIGNOR OF ONE-HALF TO VERNON H. LOCKWOOD, OF LAWRENCE COUNTY, TENNESSEE.

ELECTRIC CUT-OFF SWITCH.

SPECIFICATION forming part of Letters Patent No. 699,633, dated May 6, 1902.

Application filed October 10, 1901. Serial No. 78,163. (No model.)

To all whom it may concern:

Be it known that I, LEONIDAS W. RICHARDSON, a citizen of the United States, residing at Dustin, in the county of Lawrence and State of Tennessee, have invented certain new and useful Improvements in Electric Cut-Off Switches; and I do hereby declare the following to be a full, clear, and exact description of the invention, such as will enable others skilled in the art to which it appertains to make and use the same.

This invention relates to new and useful improvements in switches or cut-off devices used in connection with telephones or other electrical appliances, whereby the electrical connections with the outside main wire may be readily disconnected during electric storms to secure safety to life and property; and it consists particularly in the provision of a switch-lever at any convenient location which may be manipulated and securely held in a position to either close or open the circuit.

The invention relates, further, to the various details of construction and combination of parts, as will be hereinafter more fully described and then specifically defined in the appended claims.

My invention is clearly illustrated in the accompanying drawings, which, with the letters of reference marked thereon, form a part of this application, and in which drawings similar letters of reference indicate like parts in the several views, in which—

Figure 1 is a vertical sectional view through a portion of my apparatus, parts showing in side elevation. Fig. 2 is a top plan view of the invention, and Fig. 3 is a cross-sectional view.

Reference now being had to the details of the drawings by letter, A designates a bracket-arm, which is adapted for attachment to the wall of the house B or any other suitable place by screws or other means, and to said bracket-arm are secured the two yokes C and C', of similar construction, said yokes being fastened to the bracket-arm by bolts D. In Fig. 3 I have shown the stud of the yoke as recessed to receive the bracket-arm; but the two may be fastened together in any other suitable manner, if desired. The arms of the yokes are recessed to receive the ends of the

glass tubes E, and the portion of each arm projecting below its recessed part is slotted, as at F, Fig. 3, to receive the parallel portions of the frame G, and bolts G' are passed through the slotted or bifurcated ends of the arms and the frame to securely hold the yokes and frame together. A brace H is fastened at one end to the building, as shown in Fig. 1, while its other end is secured to the frame G, thereby making the supporting-frame secure and rigid.

Mounted in corresponding ends of the glass tubes are plugs K, made, preferably, of metal, said plugs having a central bore, through which the wire L passes. The inner end of each plug is chambered out and has a conical wall to receive and center the head L' on the wire L. To the opposite end of each wire is connected an electric wire M, which wires are supposed to be connected to the phone or other electric appliance. Mounted in each recess in the yoke-arms is an insulating-plug, of vulcanized rubber or other material, and each insulating-plug N is centrally apertured to receive a wire L. These wires L, it will be observed, are threaded to fit the interior threads of the metallic plugs K, so that the heads of the wires may be drawn tightly against the conical end of the bore of the plug.

Each glass tube has a guide-plug O, the circumference of which fits the bore of the tube, and through a central aperture of the guide-plug, which aperture is threaded, a wire Q passes, which wire is also threaded. These guide-plugs are adapted to move back and forth in the glass tubes in order to bring the inner ends of the wires Q into contact with the heads L' of the wires L when it is desired to close the circuit. The mechanism for actuating the guide-plugs and the wires Q consists of the strips R, of metal, which are pivoted to the switch-lever S and at their other ends are fastened to the strip of vulcanized rubber T. To the opposite end of the rubber strip T are secured the braces J, made, preferably, of metal, the other ends of said braces being fastened to the insulating-bar W, which passes through eyes formed in the ends of the braces. A spreader W' is interposed between the eyes of the braces J and serves to hold the braces apart. The outer end of each wire Q has an eye Q', and each

eye is designed to fit over said rubber insulating-bar W, and suitable insulating-washers V are interposed between the eyes Q' and the eyes at the outer ends of the braces J. To 5 each eye Q' is connected a wire X, the one connected to the ground and the other to the outside main.

One end of the switch-lever S is pivoted, as at S', to a segment S², the latter having 10 notches I to receive the end of the dog Z, which latter is mounted in a recess in the lever S. As the pivoted end of the lever S is bifurcated, the inner end of the dog will readily seat in one or the other of said recesses. A set-screw 15 P is secured to the dog and is designed to seat in a slot in the upper end of the lever S to prevent the dog from turning when in a locking relation.

From the foregoing it will be understood 20 that when it should be desired to break the circuit, as during a thunder-storm, the switch-lever is merely thrown so that the inner ends of the wires Q will be out of contact with the heads of the wires L, after which there will 25 be no danger from burning out of the connected parts with the outside main, as the supporting-frame is thoroughly insulated from the live wires. To complete the circuit, the lever is thrown in the opposite direction 30 and the points of the wires Q are brought into contact with the heads of the wires L'.

Having thus described my invention, what I claim to be new, and desire to secure by Letters Patent, is—

35 1. In combination with the insulating-tubes and supporting means therefor, a metallic plug secured within each tube, a threaded wire passing through each plug, a movable guide-plug and a threaded wire passing 40 through each guide-plug and mounted within the tubes, insulating-plugs at the ends of said tubes and through which plugs said wires pass, a switch-lever, and insulated connec-

tions between said lever and the wires passing through the guide-plugs, as set forth. 45

2. In combination with the glass tubes, the frame supporting the same, the metallic plugs, one secured in the corresponding end of each tube, each plug being centrally apertured and threaded, the inner end of the plugs being 50 chambered out in conical shape, a headed wire seated in said chambered portion, with the wire passing through the threaded aperture therein, the guide-plugs, one in each tube and centrally apertured, a threaded wire 55 passing through the apertured portion of each guide-plug, a switch-lever, and segment to which it is pivoted, a dog engaging a recess in said segment, an insulating-bar connecting the eyes at the outer ends of the threaded 60 wires engaging said guide-plugs, and a connection between the switch-lever and the insulating-bar, substantially as shown and described.

3. In combination with the bracket-arm, 65 the yokes secured thereto, the frame secured to said yokes, the glass tubes supported in recessed portions of said yokes, the metallic plugs chambered as described and seated in the ends of said tubes, the threaded wires 70 passing through threaded apertures in said plugs, the movable guide-plugs in the tubes, the threaded wires passing through threaded apertures in said movable guide-plugs and 75 having eyes at their outer ends, the switch-lever, the insulating-bar mounted in the eyes of said wire, the insulating-strip connecting the switch-lever with said insulating-bar and the insulating washers and spreader on said bar, as shown and described. 80

In testimony whereof I affix my signature in presence of two witnesses.

LEONIDAS W. RICHARDSON.
